UNITED STATES PATENT OFFICE

2,637,894

REFACING TOOL

George J. Simoleny, Cleveland, Ohio, assignor to
The Dill Manufacturing Company, Cleveland,
Ohio, a corporation of Ohio.

Application October 8, 1949, Serial No. 120,299.

3 Claims. (Cl. 29—103)

1

This invention relates to a refacing tool that is particularly adapted for refacing the ends of valve stems such as used with pneumatic tires, although the tool is adapted for other uses as, for instance, the refacing of the valve seats of faucets and other types of valves.

An object of the invention is to provide an improved and novel refacing tool which is simple in construction, is readily and economically manufactured and assembled and is efficient in use.

More particularly an object of the invention is to provide in a refacing tool an improved and novel cutter element which can be readily formed from a metal disk by simple operations, such as readily and economically produced stamping or forming and drilling operations that do not require special expensive machinery for the purpose.

A further object is to provide a refacing tool capable of cutting the end of a valve stem with a radius such that the rubber gasket in the usual valve cap will not be damaged when the cap is tightened. Ordinarily the cutting of such radius in the end of a valve stem requires the use of a cutter that is first formed to machine flat surfaces, then has its cutting edge cut away to produce the desired shape, and finally has its teeth relieved to provide clearance.

Further and additional objects and advantages not hereinbefore referred to will become apparent during the detailed description of an embodiment of the invention which is to follow.

Referring to the accompanying drawing illustrating said embodiment of the invention,

Fig. 1 is a view, partially in elevation and partially in section, of a refacing tool embodying the invention.

Fig. 2 is a sectional view on a larger scale than Fig. 1 and is taken substantially on line 2—2 of Fig. 1 looking in the direction of the arrows.

Fig. 3 is a sectional view on a larger scale than Fig. 1 and is taken substantially on line 3—3 of Fig. 1 looking in the direction of the arrows.

Fig. 4 is a detached plan view on a still larger scale of the cutter element of the refacing tool shown in Fig. 1, and

Fig. 5 is an elevational view substantially on the scale of Fig. 4 of the cutter element with the body of the tool indicated by dot and dash lines.

The refacing tool comprises a shank 10 which in this instance is hexagonal in cross-section, a handle 11 and a body 12. The handle 11 is shown for illustrative purposes in the form of an elongated cylindrical member having centrally of one

2

end thereof an inwardly extending bore in which one end of the shank 10 may have a pressed fit to secure the shank and the handle together. It will be understood that the handle might be interconnected in any other well known manner and also that the shank which is illustrated as hexagonal in cross section might have various desired cross sectional configurations.

The body 12 is of cylindrical shape and is provided with a central bore 13 extending longitudinally of the body from one end thereof and with a coaxial counterbore 14 extending centrally of the body from the other end thereof. The inner end of the counterbore 14 provides an internal shoulder 15 in the body which is shown as tapered. The shank 10 has its end remote from the handle 11 provided with a reduced portion that has a pressed fit in the bore 13 of the body. Of course the shank might be connected to the body 12 in any other desired manner.

The cutter element is indicated at 16 and is in the form of a thin metal disk as, for instance, for some uses the cutter element could be formed of .015 stock, although it is not the purpose to be limited to this gauge stock alone. The cutter element will be formed of a suitable metal which will have the requisite hardness for the purpose or which can be hardened and treated to provide it with the requisite hardness.

The disk which is formed into the cutter element may be hexagonal in configuration or may have any other multi-sided periphery as, for example, the three sided periphery shown in the drawing and wherein the points constituting the

35 intersections of the sides are indicated at 17. The cutter element 16 is provided with a central opening 18 and intermediate said opening and the periphery of the cutter element there are three equally spaced smaller openings 19. The centers 40 of the openings 19 are located on a circle the diameter of which equals the mean diameter of the usual valve stem. The cutter element is formed or bent to provide three equally spaced bowed portions or grooves 20 radiating from the central opening 18 to the periphery of the element and with the longitudinal center lines of the grooves located on a diametral center line of the openings 19. The grooves 20 are so shaped that their sides are disposed substantially at

45 right angles to each other. The connection between the sides of the grooves and the connection between the body of the element and the sides of the grooves are formed on predetermined and preferably equal radii. The bending of the material of the cutter element to form the 50

grooves 20 causes the material forming the circumferential edges of the openings 19 to be angularly disposed so as to provide cutting edges, as, for instance, disposed at an angle of substantially 45°.

The counterbore 14 in the body 12 has its side wall of general polygonal configuration, in this instance of hexagonal configuration, and the cutter element is positioned in the counterbore with the points 17 of the element located in wall angles of the counterbore as clearly shown in Fig. 2. The cutter element when positioned in the counterbore is limited in its movement in one direction by the shoulder 15 and is so arranged as to have the crests of the grooves 20 located toward the outer end of the counterbore. A cylindrical sleeve or bushing 21 has a forced or pressed fit in the counterbore 14 and retains the cutter element in position between the shoulder 15 and the inner end of the sleeve 21, it being noted, however, that the cutter element floats in the body, that is it is not clamped rigidly against the shoulder 15 by the sleeve 21.

From the foregoing it will be seen that the facing tool embodying the invention can be readily and economically manufactured and particularly with respect to the cutter element which is formed by simple inexpensive operations from a thin gauge metal disk.

It will also have been observed that the tool comprises only five parts which can be readily assembled without the necessity of using screws or other securing means. As illustrative of one use to which the tool may be put reference is had to the refacing of the valve stem such as is used in pneumatic tires. The outer end of the valve stem may be inserted into the sleeve 21 and the user of the tool then simply rotates the tool by the handle 11 with the cutter element engaging the end of the valve stem. This rotation of the tool causes the cutter element and particularly the edges of the openings 19 which contact the end of the valve stem to cut or reface such end of the stem.

Although a preferred embodiment of the invention has been illustrated and described herein it will be understood that the invention is susceptible of various modifications and adaptations within the scope of the appended claims.

Having thus described my invention, I claim:

1. A cutter element adapted to be mounted in a recess of a tool body and to be retained therein by a retaining member and comprising a disk having a peripheral configuration adapted to non-rotatably interfit the wall of the recess of a tool body, said disk being provided with bent portions extending from the periphery of the disk toward the center thereof and forming grooves adapted to face inwardly of the recess of a tool body, said disk being provided with spaced openings located in said bent portions, and said grooves formed by said bent portions having their longitudinal center lines located on diametral lines of said openings and intersecting at the center of the disk.

2. A cutter element as defined in claim 1 and wherein said disk has a central opening while said spaced openings are located intermediate said central opening and the periphery of said disk and have their centers located on a circle concentric to said central opening with said centers angularly spaced on said circle, said grooves radiating from said central opening to the periphery of said disk and having their longitudinal center lines coinciding with diametral lines of said spaced openings which intersect at the center of said central opening.

3. A cutter element as defined in claim 2 and wherein said central opening is of larger diameter than said spaced openings and the peripheral edges of the spaced openings are angularly disposed to provide cutting edges.

GEORGE J. SMOLENY.
